200,000

DISPENSING CONTAINER FOR TABLETS

Howard A. Richards and Jack L. Williams, Waukegan, Ill., assignors to Abbott Laboratories, North Chicago, Ill., a corporation of Illinois

Filed Dec. 16, 1963, Ser. No. 77,824

Term of patent 14 years

(Cl. D58—12)

We claim:

The ornamental design for a dispensing container for tablets, substantially as shown.
